UNITED STATES PATENT OFFICE.

FRANÇOIS RILLEAU, OF LOS ANGELES, CALIFORNIA.

AVIATOR-PROTECTOR.

1,027,764.

Specification of Letters Patent. Patented May 28, 1912.

Application filed January 12, 1911. Serial No. 602,346.

To all whom it may concern:

Be it known that I, FRANÇOIS RILLEAU, a citizen of France, residing at Los Angeles, in the county of Los Angeles and State of California; have invented a new and useful Aviator-Protector, of which the following is a specification.

This invention is designed to afford protection in case of accident to aviators and other riders that are liable to fall from considerable heights or from high speed machines.

The protector is a hollow walled body having a cavity for the person to be protected and may have a door in front that covers the body and legs. In some instances the door will extend down in front of the occupant's legs and in other instances will terminate above the seat a sufficient distance to accommodate the legs of the occupant.

The accompanying drawings illustrate the invention.

Figure 1 is a front elevation of a protector embodying the invention and in use with an aviator in riding position in a flying machine, portions of the steering gear of which are shown. The door extends in front of the rider's body and terminates above the level of the seat. Fig. 2 is a side elevation from the right side of Fig. 1; the aviator and the frame of the protector being indicated in dotted lines. Fig. 3 is a vertical mid-section on line x^3 , Figs. 1, 4 and 5. Fig. 4 is a plan section from line x^4 , Figs. 1, 2, and 3. Fig. 5 is a top view. Fig. 6 is a diagrammatic perspective view of the frame uncovered.

The protector comprises a hollow double walled body 1 having a cavity 2 in one side to accommodate the person of the aviator. The floor 3 of the cavity is formed by a convolution of said double wall and is spaced above the base wall 4 to form a seat for the aviator. The roof 5 of the cavity is a convolution of the hollow wall and forms the head protector.

The hollow side walls 6 have forward extensions 7 at their bottoms to form leg protectors and a double wall intermediate leg protector 8 projects forward midway between the side leg protectors 7. The material of which the walls are made is flexible, preferably being caoutchouc-covered canvas of several piy so as to be impervious to air, and the walls are inflated by air which

may be pumped in through the valved air nozzle 10. Said flexible material is held in normal shape by a frame 11, made of strong, light, metal rods; said frame being integral throughout.

The cavity 2 is closed at back, sides, top and bottom, and is open at front. Buttresses 12, 13, project inwardly from the side walls part way across the cavity. To one of these buttresses is hinged a door 14 having a latch which may be in the form of a strap 15 buttoned on a button 16 on the inner side of the other buttress.

Straps 17 may be provided at the corners 70 of the base for the purpose of fastening the protector to the frame of the vehicle to which it is to be applied.

The door and the buttress are preferably provided with notches 18 through which the arms of the user may be extended to enable him to take hold of the steering gear 19 of the flying machine or other vehicle in which he is riding.

In practice the pneumatic shield formed 80 by the hollow walled body having the cavity in front will break a fall; the body of the aviator being sustained by the cushion-like seat, back, or sides in case either strikes the ground first, and in case the front extensions and roof strike the ground first the body will be sustained by the door and the buttresses; the same serving to hold the arms and thighs of the aviator to guard against throwing the body against the roof. 90

Notches 20 at the front edges of the side walls just below the roof serve as lateral lookout openings to allow the aviator to look sidewise.

I claim:

1. An aviator protector comprising a double walled body having a cavity to accommodate a person and a double-walled roof having a frame and forming a head protector.

2. An aviator protector comprising an inflated double walled body having a cavity to accommodate a person and a double-walled roof having a frame and forming a head protector.

3. An aviator protector comprising a double walled body having a cavity to accommodate a person; said cavity being open at the front and formed with a floor, back, side walls and roof; the floor of said cavity forming a seat and the roof of said cavity forming a head protector.

4. An aviator protector comprising an inflated double walled body having a cavity formed with a floor and roof to accommodate a person; the floor of said cavity forming a seat and the roof of said cavity forming a head protector.
5. An aviator protector comprising a double walled body having a cavity in one side to accommodate a person; said cavity being formed with a floor; said floor being adapted to form a seat for a person and a roof above said seat; said roof being provided with a frame and forming a head protector.
10. An aviator protector comprising a double walled body having a cavity in one side to accommodate a person; said cavity being formed with a floor, and side walls; said floor being adapted to form a seat for a person, and there being forward extensions of the side walls of the body projecting above the level of the seat.
15. An aviator protector comprising a double walled body having a cavity in one side to accommodate a person; said cavity being formed with a roof, a floor and side walls; the floor of said cavity being adapted to form a seat for the person; and a door in front of the cavity; there being open spaces formed between the door and the floor and walls of the cavity to accommodate the legs and arms of a person.
20. An aviator protector comprising a double walled body provided with a cavity to accommodate a person and form a seat, and also provided with three forward ex-
- tensions spaced apart to accommodate the aviator's legs.
25. An aviator protector comprising an inflated double walled body provided with a cavity to accommodate a person and form a seat, and also provided with three hollow forward extensions spaced apart to accommodate the aviator's legs.
30. An aviator protector comprising a hollow pneumatic shield provided with a seat and with a cavity above the seat to accommodate the body of the aviator; said hollow pneumatic shield being provided with a frame extending into the portion of said shield above said cavity to form a head protector for the aviator.
35. An aviator protector comprising a hollow pneumatic shield provided with a seat and with a cavity above the seat to accommodate the body of the aviator and provided with buttresses, and a door above the seat to support the thighs of the aviator against movement from the seat.
40. An aviator protector comprising a hollow pneumatic shield provided with a seat and a cavity above the seat to accommodate the body of the aviator and provided with a roof and with forward extensions, and with a door in front of the cavity.
45. In testimony whereof, I have hereunto set my hand at Los Angeles, California, this 24th day of December, 1910.
50. FRANÇOIS RILLEAU.
55. In presence of—
JAMES R. TOWNSEND,
L. BELLE RICE.
